CLAIM

The ornamental design for an air moving device, as shown and described.

DESCRIPTION

FIG. 1 is a front side elevational view of an air moving device embodying my new design;

FIG. 2 is a back side elevational view thereof;

FIG. 3 is a left side elevational view thereof;

FIG. 4 is a right side elevational view thereof;

FIG. 5 is a bottom plan view thereof;

FIG. 6 is a top plan view thereof;

FIG. 7 is a back, left, and bottom side perspective view thereof; and,

FIG. 8 is a front, right, top side perspective view thereof. Broken lines are used to illustrate portions of the air moving device which form no part of the claimed design. The air moving device is shown with a symbolic break in its length. The appearance of any portion of the air moving device between the break lines forms no part of the claimed design.
